UNITED STATES PATENT OFFICE

JOHN T. RAUEN, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed September 28, 1927. Serial No. 222,662.

This invention relates to improvements in refrigerator cabinets and more particularly to the construction of doors therefor and the method of making the same.

5 It is an object of the invention to simplify the construction of refrigerator doors so as to provide a rigid and serviceable structure which will adapt itself readily to rapid quantity production.

10 It is another object of the invention to reduce the number of parts required in the construction of a refrigerator door and consequently to reduce the cost without sacrificing either the strength or efficiency of the structure.

15 A further object of the invention is to provide a door frame construction adapted to receive a plate having a brittle coating or finish, such as porcelain enamel, without the necessity of bending or bowing the plate.

With these and further objects and advantages in view the invention more particularly contemplates the production of a door having a shoulder or projection formed on a frame 25 thereof and adapted to hold in place a plate constituting one wall of the door which in turn retains the insulating panel in place.

Further objects and advantages of the present invention will be apparent from the following description, reference being had to the accompanying drawings, wherein a preferred form of the present invention is clearly shown.

In the drawings:

35 Fig. 1 shows a top cross section through the improved door of the invention.

Fig. 2 represents a front view partly broken away to show the rear plate retaining means.

Fig. 3 is a rear view of the finished door showing details of construction.

Referring in detail to the drawings, the door comprises essentially a frame composed of members 10 of which there may be four as shown in Fig. 3 and which may be joined 45 in any suitable manner as by dovetailing or the like. These end members 10 are provided with projections or tongues 11 which, when the members are joined together into a frame, provide an internally extending flange 50 somewhat similar to that of a picture frame

and which is adapted to receive an enameled or otherwise finished metal plate 12. A locking strip or cleat 13 is used for holding the metal plate 12 in position whereupon the cork or other suitable insulating panel 14 may be 55 placed in position after which the outside sheet metal covering 15 is fastened in place. The frame members 10 of the door may have projections 16 similar to flange projections 11 but located as shown in Fig. 1 so that a gasket 60 17 may be interposed between the projecting portion of the frame and the cabinet 18 to serve as a seal against the entry of warm air into the refrigerator. A hinge comprising members 19 and 20 is shown as an illustrative 65 method of attaching the door to the refrigerator and may of course be offset to permit proper seating of the door.

In assembling the door of the invention, the members 10 are first united into a frame, the 70 metal plate 12 destined to face the inside of the refrigerator is then placed so as to be held by the flange frame formed by the projections 11, after which the cleat or retaining members 13 are fastened to the members 10 75 as by nails 21 or the like. This produces a structure analogous to a metal-bottomed wooden trough into which the insulating material 14 such as cork or the like is placed. The metal sheeting destined to serve as the 80 exterior of the door is thereupon placed over the structure and held in position in any suitable manner.

While the form of embodiment of the invention as herein disclosed, constitutes a preferred form, it is to be understood that other forms might be adopted, all coming within the scope of the claims which follow.

What is claimed is as follows:

1. A refrigerator door comprising a frame 90 having an opening, a shoulder on said frame and extending inwardly beyond the walls of said opening, insulating material within the frame, means enclosing said insulating material including a plate insertable into said opening and engaging said shoulder to form one of the side walls of said door, a cover means forming a second side wall of said door, and retaining means secured to the walls 95 of said opening between said plate and said 100

cover means for retaining said plate in engagement with said shoulder.

2. A refrigerator door comprising a frame having an opening, a shoulder on said frame and extending inwardly beyond the walls of said opening, insulating material within the frame, means enclosing said insulating material including a plate insertable into said opening and engaging said shoulder to form one of the side walls of said door, a cover means forming a second side wall of said door, and retaining means secured to the walls of said opening between said plate and said cover means for retaining said plate in engagement with said shoulder, said retaining means having a rectangular cross-section and extending from said plate to said cover means.

3. A refrigerator door comprising a frame having an opening and a shoulder integrally formed on said frame and extending inwardly beyond the walls of said opening, a plate having a brittle coating insertable into said opening and being adapted to engage said shoulder to form one of the side walls of the door, a cover forming a second side wall of the door, and removable retaining means between said plate and said cover for maintaining engagement between said plate and said shoulder.

30 4. A unitary cover for an opening in a refrigerated cabinet comprising a body member composed of insulating material having an outwardly extending top flange and an inwardly extending bottom flange, a bottom 35 cover plate supported upon said bottom body flange, a top cover plate bent around said top body flange, and insulation means within said body intermediate said cover plates.

5. A unitary cover for an opening in a refrigerated cabinet comprising a body member composed of insulating material having an inwardly extending bottom flange, a bottom cover plate supported by said bottom body flange, a top cover plate, and insulation 45 material intermediate said plates.

6. A cover for a refrigerated cabinet comprising a sleeve of heat insulating material provided at one end with a continuous inwardly projecting flange and at the other 50 end with a continuous outwardly projecting flange, a member adapted to close one end of said sleeve and secured in position by means of said inwardly projecting flange, a sheet metal member adapted to close the other 55 end of said sleeve and having its peripheral edge bent around said outwardly projecting flange, and a body of heat insulating material disposed within said sleeve.

60 In testimony whereof I hereto affix my signature.

JOHN T. RAUEN.
